SADDLE FIXING FOR THERMIONIC VALVE HOLDERS AND OTHER ELECTRICAL COMPONENTS

Stanley Thomas Deakin, Ewell West, England, assignor to British Mechanical Productions Limited, Leatherhead, England, a British company

Application July 6, 1945, Serial No. 603,520
In Great Britain April 17, 1944

3 Claims. (Cl. 173—339)

1

This invention relates to saddle fixings for thermionic valve holders and other electrical components.

The invention is particularly (but not exclusively) concerned with thermionic valve holders of the type comprising an insulating barrel providing at one end a number of sockets to receive the contact pins of the valve and at the other end a corresponding number of tags or equivalent terminal elements to take the circuit wiring connections. For the purpose of securing the valve holder in position, e.g. to the chassis of a wireless set, it is customary to provide the barrel at a position intermediate in its depth, with an attached flange-forming plate or saddle usually of metal in which apertures are formed to receive fixing screws or bolts. It is desirable that the holder should be capable of being presented through the hole in the chassis panel or equivalent fixture from either side of the panel; i.e. with the saddle disposed to one side or the other of the panel, and moreover that the barrel should have the same circumferential dimension on each side of the saddle. To meet these requirements it has previously been proposed to embed the saddle, as an insert, in the material of the insulating barrel during the moulding of the latter. There are, however, manufacturing difficulties in connection with such an assembly and it is not applicable where the barrel is made of certain material such as ceramics because the metal of the saddle would fuse under the high temperature conditions under which ceramic moulding is necessarily carried out.

An object of the present invention is to provide an improved method of securing a saddle to an insulating barrel having a substantially uniform circumferential dimension throughout its depth.

According to the invention an electrical component (e.g. a thermionic valve holder) of the type comprising an insulating barrel and an attached flange-forming plate or saddle having an aperture in which the barrel is located, is characterised in that the saddle is secured to the barrel by means of two tongues (or two sets of tongues) which project inwardly from the periphery of the locating aperture in the saddle at circumferentially spaced intervals and are adapted to engage respectively two internal ledges (or two sets of ledges) formed in the circumferential wall of the barrel, one tongue (or set of tongues) preventing movement of the saddle in one direction along the barrel and the

other tongue (or set of tongues) preventing movement of the saddle in the opposite direction along the barrel.

The invention includes an electrical component 5 in which one saddle tongue (or set of tongues) is permanently in the general plane of the saddle, and, in order to permit assembly, the other saddle tongue (or set of tongues) is initially bent back at right-angles to the plane aforesaid, being subsequently bent over into that plane to engage the co-operating barrel ledge (or set of ledges).

The invention also includes an electrical component 15 in which one saddle tongue (or each of a set of saddle tongues) is in the form of a fork 10 extending at right-angles to the general plane of the saddle and having its prongs splayed apart to engage a co-operating ledge in the barrel.

Two examples embodying the invention as applied to thermionic valve holders will now be described with reference to the accompanying drawings which are to some extent diagrammatic and in which:

Figure 1 is a perspective view of the saddle, 25 prior to assembly, used in the first example;

Figures 2 and 3 are perspective views looking on opposite sides, respectively, of a valve holder with assembled saddle according to the first example;

Figure 4 is a perspective view of the saddle, 30 prior to assembly, used in the second example;

Figure 5 is a perspective view of the barrel of the valve holder according to the second example, the assembled saddle being shown in dotted lines, and

Figure 6 is a side elevation of the saddle in the form it may take before assembly.

In the first example (Figures 1, 2 and 3) the valve holder comprises an insulating barrel 10 formed with a circular series of axial apertures 11 which accommodate single piece metal contact elements providing at one end 12 of the barrel (hereinafter referred to as the top) sockets 13 to receive the contact pins of the valve and at the other end 14 (hereinafter referred to as the bottom) tags 15 to take the circuit wiring connections. The barrel 10 is formed with four grooves 16 (hereinafter referred to as the fixed tongue grooves) extending parallel with the axis of the barrel inwardly from the bottom 14 to positions short of the top 12, the grooves 16 being spaced apart circumferentially at equal intervals. At the periphery of a central cut-out 17 in a saddle plate 18 (provided with 45 fixing-screw apertures 19) four tongues 20 (here-

inafter referred to as the fixed tongues) spaced apart circumferentially at equal intervals, are arranged to project, in the general plane of the saddle 18, into the central cut-out 17. The fixed tongues 20 on the saddle are shaped to mate with the fixed tongue grooves 16 in the barrel.

The peripheral wall of the barrel is also formed with four grooves 21 (hereinafter referred to as the hinged tongue grooves) extending parallel with the barrel axis to positions short of the bottom 14 of the barrel where the grooves are stepped down in width to form short narrow-width slots 22 which are continued out to the bottom of the barrel. Each of the hinged tongue grooves 21 is located equidistantly between two of the fixed tongue grooves 16. At the periphery of the central cut-out 17 the saddle 18 is also formed with four tongues 23 (hereinafter referred to as the hinged tongues) arranged to extend into the central cut-out in a direction substantially at right-angles to the general plane of the saddle. Each of the hinged tongues 23 is located equidistantly between two of the fixed saddle tongues 20. Each hinged tongue 23 is split longitudinally to form a fork, the overall width of which is initially slightly less than the width of the continuation slot portions 22 of the hinged tongue grooves 21 in the barrel.

To assemble the saddle 18 the latter is threaded on to the barrel with the fixed tongues 20 riding in the co-operating saddle grooves 21. The saddle is pressed inwardly to the limit of its travel, that is until the fixed saddle tongues 20 are in abutment with the ledges formed at the ends of the corresponding barrel grooves 16. In this position of the saddle the hinged tongues 23 extend in a direction towards the bottom 14 of the barrel, the short continuation slots 22 of the hinged tongue grooves having permitted passage of the hinged tongues along the barrel. In order to lock the saddle in position the forked arms of each hinged tongue 23 are splayed, by any suitable tool, so as to engage the ledges formed at the step in the width of the hinged tongue groove.

While in the foregoing example there are four fixed tongues and four hinged tongues co-operating with corresponding numbers of barrel grooves, it is to be understood that there may be any desired number of tongues and grooves in each set, the barrel grooves being located at convenient positions in relation to the contact sockets.

In carrying out the foregoing example the hinged tongues of the saddle may be so arranged that by virtue of their natural springiness they will spring into engagement with their co-operating barrel ledges, i. e. without necessitating the use of the expanding tool.

In the second example the peripheral wall of an insulating barrel 30 is formed at locations displaced circumferentially with two sets of grooves 31, 32 extending parallel with the axis of the barrel inwardly from opposite ends of it respectively and terminating intermediate in the depth of the barrel at positions such that the inner ends of the grooves 31 extend beyond the inner ends of the grooves 32 by an amount substantially equal to the thickness of the saddle plate 33 which is to be attached to the barrel. At the periphery of the central cut-out 34 in the saddle two sets of tongues 35, 36 are provided for engagement respectively in the grooves 31, 32 in the barrel. To permit assembly, the tongues 36 on the saddle, conveniently referred to as the hinged tongues, are initially bent back to posi-

tions at right-angles to the general plane of the saddle (as shown in Figure 4). The other tongues 35, conveniently referred to as the fixed tongues, are permanently in the general plane of the saddle, projecting into the central cut-out 34. To assemble the saddle 33 the latter is threaded on to the barrel 30 with the fixed tongues 35 riding in the co-operating saddle grooves 31. The saddle is pressed inwardly to the limit of its travel, that is until the fixed saddle tongues 35 are in abutment with the ledges formed at the ends of the corresponding barrel grooves 31. When in this position the hinged saddle tongues 36 are bent over into the co-operating barrel grooves 32 and on to abutment with the ledges at the inner ends of these grooves. In principle the saddle may be clamped by means of one fixed and one hinged tongue and two co-operating barrel grooves. In practice, however, in order to obtain a secure fixing, it is desirable to employ two sets of fixed and hinged tongues and corresponding sets of grooves extending inwardly from opposite ends respectively of the barrel, the grooves being located at convenient positions between the electrodes (some of which are indicated at 40 in Figure 5). If desired, the saddle plate may be originally dished, as shown in Figure 6, being bent back flat on assembly. By this means it is possible to take up the tolerance which would necessarily have to be provided in the tongue-and-groove engagement where the barrel is made of ceramic material.

The term "barrel" as used herein is intended to cover any insulating body, cylindrical, rectangular or of other convenient shape, to which a saddle is to be attached. While the invention is of particular applicability to holders made of ceramic material, it is to be understood that the barrel may be of any desired insulating material, e. g. a synthetic resin moulding.

It is within the invention to employ an arrangement of co-operating saddle tongues and barrel ledges which requires partial rotation of the saddle in relation to the barrel to effect the anchoring of the saddle. It is also to be understood that a securing tongue may be formed, after location of the saddle in the barrel, by upsetting or otherwise deforming a portion of the material of the saddle to constitute a tongue-like part engaging a co-operating ledge or similar abutment on the barrel.

I claim:

1. A thermionic valve holder comprising an insulating barrel, contacts supported on the barrel, and an attachment saddle consisting of a substantially flat plate surrounding the barrel and secured to the barrel intermediate in the length thereof by two sets of spaced tongues of which the tongues of at least one set are upstanding from one face of the plate and are so bent that their ends engage ledges formed in the circumferential wall of the barrel on one side of the saddle to prevent movement of the saddle along the barrel in the direction of that side and of which the tongues of the other set engage ledges in the barrel to prevent movement of the saddle along the barrel in the other direction, the barrel having the same circumferential dimension on each side of the saddle, and the upstanding tongues aforesaid being each of two-pronged construction splayed apart at their ends to engage the ledges on the barrel as aforesaid.

2. A thermionic valve holder comprising in combination an insulating contact-supporting barrel made in a single piece and having a sub-

stantially uniform circumferential dimension throughout its depth and an attachment saddle in the form of a substantially flat plate provided with a central aperture for the reception of the barrel and secured thereto intermediate in the depth thereof by interlocking devices consisting of two sets of axially parallel grooves, with those of one set alternating with those of the other, recessed in the peripheral wall of the barrel at circumferential intervals and extending inwardly from opposite ends respectively of the barrel and terminating in ledges intermediate in the depth of the barrel at positions such that the inner ledge-forming ends of the grooves of one set lie on one side of the saddle plate and extend beyond the inner ledge-forming ends of the grooves of the other set, which latter ends lie on the opposite side of the saddle and two sets of circumferentially spaced tongues formed integrally with the saddle at the aforesaid aperture therein to extend inwardly from the perimeter thereof into engagement with the ledge-forming ends of the aforesaid two sets of grooves in the barrel, the arrangement being such that one set of tongues and their associated barrel ledges prevent movement of the saddle in one direction along the barrel, while the other set of tongues and their associated barrel ledges prevent movement of the saddle in the opposite direction along the barrel.

3. A thermionic valve holder according to 30

claim 2 in which the inner ledge-forming ends of the grooves of one set extend beyond the inner ledge-forming ends of the grooves of the other set by an amount substantially equal to the thickness of the saddle, and in which one set of tongues is permanently in the plane of the saddle plate and, in order to permit assembly of the holder, the tongues of the other set are, before assembly, upstanding from the plane of the plate and after assembly of the saddle and the barrel are bent down into the plane of the plate to engage the co-operating barrel ledges.
